ABSTRACT OF THE DISCLOSURE

A fin-and-tube heat exchanger for baseboard radiators and the like wherein the fins have laterally opening undercut notches or recesses at their lower corners. Plastic corner rails having a thin slat-like, vertically oriented body portion are assembled to the fins alongside their lower corners by pairs of integral flexible fish hook formations which fit into and are retained in the notches.

BACKGROUND AND OBJECTS OF THE INVENTION

The present invention relates in general to fin-and-tube heating element assemblies for baseboard radiator structures and like applications, and more particularly to such fin-and-tube heating element assemblies having plastic corner rails of a novel construction assembled with the fins in a novel manner to accommodate movement of the fin-and-tube assembly during expansion and contraction.

In conventional fin-and-tube heating elements, the tube or liquid conduit portion is normally constructed of copper tubing to carry the water or other liquid heating medium to the heating element and produce heating of the tube and fins to effect thermal exchange with the air and produce appropriate heating of the room. Such units are frequently provided in baseboard radiator systems, wherein relatively long units or long installations are provided, usually along the outside walls of each room. Customarily, the fin-and-tube heating element assemblies for baseboard radiators are formed to appropriate lengths for the outside wall of the room or the heat requirements of the room, and are positioned with the edges of the fins, or portions of the tubes between successive fins, on supporting brackets or arms to support the fin-and-tube assembly close to the building wall adjacent the floor of the room. A baseboard radiator cover is located outwardly from the wall in covering relation to the fin-and-tube assembly defining an air inlet at the floor level below the fin-and-tube assembly and a heated air outlet at the top of the baseboard radiator unit. Such fin-and-tube heater units are also used in a number of other types of air heat exchangers.

It will be appreciated that when heat is being demanded in the room served by a particular heating element unit and heated water is caused to flow through the copper tubes of the fin-and-tube heating element, the water temperature reaches about 200 degrees F., and the copper tube expands approximately $\frac{3}{8}$ of an inch for every 10 to 12 linear feet. Likewise, when the heat demand is satisfied and the thermostatic controls terminate flow of heated water through the copper tubes of the heating element, the copper tube contracts as the water temperature in the tubes returns to approximately room temperature of about 65 degrees F. This expansion and contraction of the heating element has created particular problems, such as noise arising during expansion and contraction, due to sliding of fins over the supporting brackets, possible damage to the edges of the fins or fins which may catch on surfaces or portions of the supporting brackets during expansion, and possible distortion of the heating element unit when the construction is unable to freely accommodate the thermal expansion and contraction.

2

Heretofore, attempts have been made to alleviate this problem by providing corner tracks assembled at each of the four corners of the plurality of fins in a fin-and-tube heating element assembly, but problems have persisted as to distortion of the fins or resistance to free movement of the fins toward and away from each other during expansion and contraction of the copper tubes on which they are mounted, because of the frictional restraining force usually present as an incidence to the assembly of the corner tracks on the fins of such fin-and-tube heating elements. The problem of providing corner rails which can be readily assembled to the fins of fin-and-tube heating elements and which still permit appropriate movement of the fins relative to the rails without undue restraint by the corner rails as the copper tube expands and contracts has been especially acute when plastic corner rails are used.

An object of the present invention is the provision of a novel plastic corner rail and fin-and-tube heating element assembly for baseboard radiator systems and the like wherein the rails serve to reinforce the unit and facilitate handling thereof during installation, and facilitate support of the heating element assembly on the conventional rail supports of the radiator unit, wherein the corner rails are made of plastic having a shape which facilitates their assembly with the fins and permits the fins to freely move relative to the rails on expansion and contraction of the copper tube of the heating element assembly.

SUMMARY OF THE INVENTION

The present invention is directed to a fin-and-tube heating element assembly for baseboard radiators and the like wherein the lower corners of each of the fins are provided with slots having an enlarged or undercut portion spaced inwardly from the lateral vertical edges of the fins, communicating by a constricted slot portion with the adjacent vertical fin edge, with the constricted slot portion joining an outwardly divergent or flaring entrance end opening through the lateral edges of the fins. A plastic corner rail extending the length of the fin-and-tube assembly is provided with a slat-like body portion in the form of a thin narrow flat strip to lie in a vertical plane immediately adjoining the adjacent vertical lateral edge of the fins with its lower edge extending slightly below the bottoms of the fins, and has a pair of generally fish hook shaped projections with the hook portions extending in relatively opposite directions projecting from the slat-like body portion into the slots with the hook portions lying in the enlarged or undercut portions of the slots.

BRIEF DESCRIPTION OF THE FIGURES

FIG. 1 is a fragmentary perspective view of the plastic corner rail and fin-and-tube heating element assembly embodying the present invention, showing a representative short length of the heating element unit;

FIG. 2 is a fragmentary side elevation view of a short length of the heating element assembly;

FIG. 3 is a perspective view of a length of the corner rail strip, viewed from the inner side thereof;

FIG. 4 is an enlarged cross-section view of the corner rail, taken along the line 4—4 of FIG. 3; and

FIG. 5 is a vertical section view through the heating element assembly, taken along the line 5—5 of FIG. 2, and showing the heating element assembly installed in a typical baseboard radiator unit shown in vertical section.

DETAILED DESCRIPTION OF A PREFERRED EMBODIMENT

Referring to the drawings, wherein like reference characters designate corresponding parts throughout the several figures, the heating element assembly of the present invention is indicated generally by the reference char-

acter 10 and comprises a copper tube 11 on which is fitted a plurality of spaced apart fins 12. The fins 12 have a generally rectangular body portion 13 with rounded upper corners and have relatively narrow vertical flanges 14 at the vertical lateral edges of the body portions and an aperture in the approximate center of the fin body 13 bounded by an annular cylindrical flange 15 sized to tightly fit on the copper tube 11 and be secured in coaxial surrounding relation to the copper tube 11 in the usual manner.

The lower corner portions of the fins 12 adjacent the lateral edges thereof are provided with specially shaped slots or notches 16, each of which have an outwardly flaring or divergent entrance portion 16a opening through the lateral edge and flange portion of the associated fin, a constricted portion 16b spaced inwardly from the edge and communicating with the entrance portion 16a, and an enlarged rectangular undercut portion 16c inwardly communicating with the constricted portion 16b and defining, in effect, an undercut recess having restraining shoulders 17 facing inwardly towards the center plane of the plurality of fins.

The slots or notches 16 are adapted to receive longitudinally continuous intercoupling projections 19 of plastic corner rail members 20 to couple the rail members in proper position on the fins 12. The plastic corner rail members 20 are integral molded extrusions formed from suitable plastic material having a relatively thin narrow slat-like body portion 21 defining a continuous elongated strip or rail of uniform height providing a lower edge 21a positioned slightly below the bottom edges of the fins 12 to rest on support brackets, spaced along the axial length of the base board radiator, such for example as the bracket 22 illustrated in FIG. 5. The bracket 22, as illustrated, extends outwardly from the building wall 23 and is spaced an appropriate distance above the floor 24 to provide a return air inlet 25 below the heating element assembly 10, and forms the lower support for the front cover panel 26 of the baseboard radiator. Additional supporting brackets 27, not relevant to the heating element structure of the present invention, provide support for the upper edge of the front cover panel 26 and the top cover sheet 28, as well as for an adjustable damper 29 in the upper air outlet or discharge opening 30.

The rail members 20, as illustrated more particularly in the enlarged cross-sectional view of FIG. 4, has projecting from the slat-like body portion 21 at a location about $\frac{2}{3}$ the way up the height of the body portion a pair of vertically spaced intercoupling projections 19 of generally fish hook shaped cross-sectional configuration, each including a web portion 19a and a hook portion 19b defining a shoulder 19c which is inclined at an acute angle to the plane of the surface of web portion 19a which it joins. The two fish hook shaped web portions 19a are sufficiently flexibly deformable so that they can be readily forced into coupling relation with the undercut notches or slots 16. This is accomplished by forcing the fish hook shaped web portions 19 to the left, with reference to FIG. 4, or inwardly toward the center plane of the fins, to bring the rounded portions of the hook formations 19b into engagement with the flared entrance portion 16a of the notches. The converging surfaces of the flared portion 16a force the hook portions 19b toward each other to permit them to pass through the constructed portion 16b of the slots 16. When the rails are forced fully to the position illustrated in FIG. 4, the surface portions 19c of the hook formations 19b snap outwardly, due to the elastic memory of the web portions 19, and lap the restraining shoulders 17 of the enlarged portions 16c of the recesses to hold the rail members 20 in assembled relation with the fins.

By this construction, the plastic rails are easily inserted into the notches of the fins and therefore assembled with the fins of the heating elements, but the rails are not rigidly connected to the fins or restrained by frictional pressure

against movement to any extent which will retard relative movement of the fins toward or away from each other as the copper tube 11 expands and contracts. It will be appreciated that the water in the copper tubes 11 is normally at approximately 65 degrees F., and when heat is demanded in the room or the portion of the baseboard radiator serving the space sensed by the thermostat, the water temperature of the heated water which flows through the tubes during heat demand reaches about 200 degrees 10 F. This causes the copper tubes to expand approximately $\frac{3}{8}$ of an inch in 10 to 12 linear feet, thus necessitating some relative movement of the fins 12 away from each other as an incident to this expansion. The plastic rails, however, still remain at approximately their normal room 15 temperature, or at least do not get over about 75 degrees F., because the return air stream entering inlet 25 of the radiator unit below the front cover panel 26 and passing over the plastic rails does not exceed this temperature range. Because of the particular construction of the web 20 portions 19 of the rail members and the configuration of the slots 16, the fins are allowed to readily move toward and away from each other as required by contraction and 25 expansion of the copper tube 11 without distortion of the heating element and without the pinging noises normally caused by expansion and contraction of heating elements, the fish hook web portions 19 being of such nature that they do not exert sufficient restraining frictional pressure on the fins to hold the fins against movement responsive to expansion and contraction of the copper tube. Furthermore, the rail is not easily removed from the fin, thus 30 allowing the fin sections to be cut to size easily as well as permitting them to be handled with less care than is required with many other units presently available.

What is claimed is:

- 35 1. An elongated fin-and-tube heating element unit for baseboard radiators and the like wherein the heating element unit extends along a horizontal longitudinal axis and is supported on upwardly facing horizontal surfaces of support brackets; the heating element unit comprising an axially elongated cylindrical metal tube for conducting heating liquids, a plurality of metal fins arranged in parallel vertical planes perpendicular to the axis of the tube fixed on the tube with the tube passing through the fins, the fins having aligned horizontal lower edges and respective pairs of opposite vertical lateral edges and having undercut notches opening outwardly through the opposite lateral edges, a pair of corner rails each of integral molded plastic material extending continuously along the length of the plurality of fins at the lower 40 corners thereof where said lateral edges join said lower edges, the corner rails each including a slat-like body portion in the form of a vertically oriented thin narrow flat strip of generally rectangular cross-section to lie alongside the lower portions of said lateral edges with its bottom edge bearing on said surfaces of said support brackets, and a pair of integral fish-hook shaped coupling projections extending into said notches, said projections including thin flexible web portions extending in parallel vertical spaced horizontal planes along the 45 length of each respective body portion and having enlarged hook formations on the inner ends thereof extending in relatively opposite directions into the undercut portions of said notches to restrain the associated corner rail against withdrawal while readily permitting relative movement of the fins along the longitudinal axis of the corner rail.

50 2. A fin-and-tube heating element unit as defined in claim 1, wherein the hook formations of said coupling projections in each corner rail have semi-cylindrical leading surfaces facing toward the longitudinal center axis of the unit and define restraining shoulders facing outwardly toward the lateral edges of the fins and inclined at acute angles to the web portions.

55 3. A fin-and-tube heating element unit as defined in claim 1, wherein said undercut notches each include a

vertically enlarged inner portion sized to accommodate said hook formations, a constricted portion outwardly adjoining the enlarged inner portion, and an outward flaring divergent entrance portion outwardly adjoining the constricted portion and opening through the adjacent lateral edge of the associated fin for camming the hook formations inwardly to pass through said constricted portion upon insertion of the coupling projections into the notches.

4. A fin-and-tube heating element unit as defined in claim 2, wherein said undercut notches each include a vertically enlarged inner portion sized to accommodate said hook formations, a constricted portion outwardly adjoining the enlarged inner portion, and an outward flaring divergent entrance portion outwardly adjoining the 15 constricted portion and opening through the adjacent

lateral edge of the associated fin for camming the hook formations inwardly to pass through said constricted portion upon insertion of the coupling projections into the notches.
